ENDGATE LOCK

Philip D. Baldauf, Bridgeport, Ind., assignor to
General Motors Corporation, Detroit, Mich., a
corporation of Delaware

Application February 1, 1940, Serial No. 316,809

7 Claims. (Cl. 292—26)

This invention relates to vehicle bodies and has particular reference to a latch mechanism and its application to an upwardly swinging door and downwardly swinging end gate to the rear end of a commercial body.

The object of the invention is to construct a latching mechanism mounted at the meeting line of the door and gate and which latching mechanism will hold both the door and the end gate in latched position. Another object of the invention is the provision of an operating means which will operate the latching mechanism to release the door without unlatching the end gate so that the door may be swung upwardly and the end gate retained in latched position. A further object of the invention is the provision of a latching mechanism which may be operated to release either the door only or both the end gate and the door.

Further objects of the invention relate to details of construction.

On the drawings—

Figure 1 is a side view of the rear part of a commercial body showing the door in raised position and end gate in lowered position in dotted outline.

Figure 2 is a rear end view of the structure of Figure 1, with parts broken away better to show details of construction.

Figure 3 is a view of one of the latches secured to the body at the meeting line of the door and end gate, taken on the line 3—3 of Figure 2.

Figure 4 is a section on the line 4—4 of Figure 3.

Figure 5 is a section on the line 5—5 of Figure 4.

Figure 6 is a section on the line 6—6 of Figure 7.

Figures 7 and 8 are detailed sectional views on the corresponding lines of Figure 2.

Figure 9 is a sectional detailed view on the line 9—9 of Figure 8, the open position of the door being shown in dotted outline.

Referring to the drawings, the numeral 2 indicates a commercial body as a whole. The body has the rear window 4 and rear fenders 6 which project over the usual wheels (not shown). The rear of the body is provided with an upper door 8 hinged at 10 and a lower or end gate 12 hinged at its lower end at 14. When the door 8 and the end gate 12 are closed, they meet on a common line 16.

If desired, the rear door 8 may be provided with windows 18.

The body 2 preferably has the rabbets 20 at its

sides to receive the edge flanges 22 of the door and the end gate and in between the flanges 22 and the bottom of the rabbets 20 suitable rubber strips 24 are provided to make a weathertight connection.

At the side of the opening in the rear of the body and at the line 16 there is secured to the body upright 25 the bracket 26, there being one bracket at each side of the vehicle, and as the brackets are identical a description of one will suffice for both. The brackets are secured in place by means of the screws 30 which pass through openings in ears 32 extending beyond the end of the bracket. The bracket is provided with the ears 34 which project away from the bracket and toward the end gate and door, and in the ears 34 there is mounted the rod or shaft 36, this rod or shaft preferably being secured in position.

On the rod 36 there are turnably mounted the long cylinder 38 and the short cylinder 40. The long cylinder 38 is provided with a projecting finger 42 near one end and a hook 44 adjacent the other end, and at a place substantially diametrically opposite the hook 44, a limiting stop 46 projects from the cylinder 38. This stop 46 engages with a projecting abutment 48 on the bracket 26 to limit the movement of the cylinder 38.

The short cylinder 40 has a hook 50 substantially the same as the hook 44, and a limit stop 52, similar to the limit stop 46. This limit stop 52 also engages a projection 48 on the bracket 26.

The two cylinders 38 and 40 meet along the line indicated at 54 and along this meeting line the edge face of the cylinder 38 is provided with a recess 56 while the cylinder 40 is provided with a tongue 58 which projects into the recess 56.

The recess 56 is considerably wider than the tongue 58 for a reason which will be later explained.

At the end of each cylinder 38 and 40 and adjacent the ears 34, springs 60 are provided. One end of the springs 60 is secured in a recess 62 in the bracket 26 while the other end is secured in a recess 64 in the cylinder 38 or 40. The springs always urge the cylinders and the hooks 44 and 50 into engaging position or the position shown in Figure 4.

On the inside of the door 8 and of the end gate 12, keepers or catches 66 are mounted. There is one keeper or catch at each side of the door and of the end gate. The catches 66 on the end gate are adapted to be engaged by the

hooks 58 and the catches 66 on the door are engaged by the hooks 44 to hold the end gate and door in position. In the position of the parts shown in Figure 4, both the door and the end gate are held in closed position by the latching mechanism. Each catch 66 is secured in place by means of the machine screws 67 which pass through the bracket and the end gate 12 (or door 8) and are screwed into the reinforcing iron 68.

In order to operate the latch mechanism, the rods 68 are provided. These rods are mounted at their outer ends in bearings 70 secured in the edge flange 71 of the end gate and at their inner ends they are pivoted at 72 to oppositely directed levers 74 mounted on a stud 76, rotatably secured in a small frame 78, which in turn is secured in a larger frame 80 forming a part of the inner reinforcing structure of the end gate. A spring 82 has one end 84 secured in a recess in the stud and the other end 86 secured to the frame 78 and always tends to return the rods 68 and their associated mechanism to the position shown in Figure 6, or in a position in which the ends 88 of the rods are out of engagement with the fingers 42. The ends 88 are always in alignment with the fingers 42 and by turning the handle 90 (which is secured to the stud 76) the stud will be operated to cause the levers 74 to swing and thereby to move the rods outwardly and cause the ends 88 of the rods 68 to engage the fingers 42 and move the cylinders 38. The movement of the cylinder 38 a short distance will cause the hook 44 to become disengaged from the keeper 66 on the door, and after the keepers have been disengaged the door may be raised. This initial movement of the cylinder 38 will not disengage the hook 58 from the keeper 66 on the end gate because a limited amount of lost motion is allowed because of the difference in width of the recess 56 compared to the tongue 58. If the operator should desire to release the end gate, it would be necessary to swing the handle 90 farther to the left (Figures 2 and 6) to cause the ends 88 of the rods to move the finger 42 a greater distance so as to cause the end of the recess 56 to engage the tongue 58 to cause a rotation of the cylinder 40 on the rod or shaft 36. This rotation will cause the hooks 58 to become disengaged from the keepers 66 on the end gate to enable the operator to lower the end gate. When the end gate has been moved outwardly the handle may be released to enable the spring 82 to withdraw the rods and also to enable the springs 60 to return the cylinders 38 and 40 to the position shown in Figure 4 and thereby cause a re-engagement of the hook 44 with the keepers 66 on the door. This will hold the door in latched position while the end gate is open.

A novel hinge is used to suspend the door. Two hinges are used and as they are identical, a description of one will suffice for both.

Both hinges are mounted inside the upper edge of the opening in the vehicle and to mount the hinges the transverse reinforcing bar 91, generally U-shaped in cross section, is secured to the upper edge. This bar 91 has the inner long flange 92 and the outer shorter flange 94. The outer flange is outwardly bent at 96 and upwardly bent at 98 and a flange 100 on the edge of the roof 102 is secured to the outwardly flanged part 96 as by welding and parts 96, 98, and 100 form a rain trough or channel.

The web of the channel 91 is provided with an 75

opening 106 through which there projects part of the frame 108 of the hinge. The frame has the flanges 110 at the bottom thereof, these flanges being bent in opposite directions and secured as by welding to the underside of the web of the channel 91. Over the frame members 108 there is positioned the outer frame part 112. The parts 108 and 112 may be secured together in any suitable way.

10 The door 8 has rigidly secured thereto the gooseneck bracket 114. This bracket is fork-shaped as indicated by the tines 116 in Figure 9. The ends of these tines have a guide pin 118 passing therethrough, one end of the guide pin 118 being provided with a head 120 which fits on the outside of the frame member 108, while the other pin end is screwed into the other frame member 108. A link 124 is pivoted at 126 between the tines of the bracket 114 and is journaled at 128 to the side frame members 108 of the hinge.

15 In the movement of the door from the full line position of Figure 8 to the dotted line position, the pintle or pin 118 will ride in the slot 122 while the link 124 will move on its pivot 126 to cause the door 8 to have an upward and outward movement to prevent the upper edge 130 from binding against the rain trough formed by parts 98 and 100.

20 In Figure 3 the end gate 12 is shown as having an upwardly projecting flange 132 while the door 8 has the downwardly projecting flange 134. In the closed position of the door and end gate the flange 134 overlaps the flange 132 to prevent the entrance of water. If desired, either the flange 25 132 or the flange 134 may be provided with a strip of rubber similar to the strip 24 to form a weathertight connection.

I claim:

1. In a latch for a door, a supporting bracket 40 rigidly mounted on the door frame, a shaft mounted in the bracket, two cylinders mounted for rotation on the shaft, latching hooks on the cylinders, a notch in the end of one cylinder, a tongue on the other cylinder, said tongue projecting into the notch and said notch being considerably wider than the tongue, operating mechanism, means on one of said cylinders adapted to be moved by said operating mechanism to move the cylinder, said one cylinder moving the 45 second cylinder through the interengagement of the notch and tongue.

2. In a latch mechanism for the rear door and the end gate of a vehicle body, said door being hinged at its top edge and said end gate being 50 hinged at its bottom edge, said door and said end gate meeting on a common line, brackets mounted on the vehicle at the sides thereof across the line of junction of the door and the end gate, latches pivotally mounted on the brackets, catches secured to the door and to the end gate adjacent the latches and adapted to be engaged by the latches to hold the door and the end gate in latched position, the part of each latch holding the door in latched position being movable 55 relative to the part of the latch holding the end gate in latched position, spring means constantly urging said latches into engagement with the catches, and means normally out of contact with the latches and mounted on the end gate and operable from the outside of the vehicle body to operate the latches to cause them to become disengaged from their catches to enable the operation of the end gate or the door.

3. In a latch mechanism for the rear door and the end gate of a vehicle body, said door being

hinged at its top edge and said end gate being hinged at its bottom edge, said door and said end gate meeting on a common line, brackets mounted on the vehicle at the sides thereof across the line of junction of the door and the end gate, latches pivotally mounted on the brackets, catches mounted on the door and on the end gate, said catches being adjacent the latches and adapted to be engaged by the latches to hold the door and the end gate in latched position, the part of each latch holding the door in latched position being movable relative to the part of the latch holding the end gate in latched position, spring means constantly urging said latches into engagement with the catches, and means mounted on the end gate and operable from outside the vehicle body to operate the latches to cause them to become disengaged either from the door only or from both the end gate and the door to enable the operation of either the door only, or the operation of both the end gate and the door.

4. In a latch mechanism for the rear door and the end gate of a vehicle body, said door being hinged at its top edge and said end gate being hinged at its bottom edge, said door and said end gate meeting on a common line, brackets mounted on the vehicle at the sides thereof across the line of junction of the door and the end gate, latches pivotally mounted on the brackets, catches mounted on the door and on the end gate, said catches being adjacent the latches and adapted to be engaged by the latches to hold the door and the end gate in latched position, the part of each latch holding the door in latched position being movable relative to the part of the latch holding the end gate in latched position to enable the release of the door without releasing the end gate, means constantly urging said latches into engagement with the catches, two fingers, one finger on each of said latches, rods slidably mounted on the end gate and extending away from each other, means to operate said rods to cause them to move toward the latches to cause them to be engaged with the fingers to enable the operation of the latches to cause the latches to release the catches to enable the operation of the door and the end gate.

5. In a latch mechanism for the rear door and the end gate of a vehicle body, said door being hinged at its top edge and said end gate being hinged at its bottom edge, said door and said end gate meeting on a common line, latches mount-

ed on the vehicle at the sides thereof across the line of junction of the door and the end gate, catches mounted on the door and on the end gate, said catches being adjacent the latches and adapted to be engaged by the latches to hold the door and the end gate in latched position, the part of each latch holding the door in latched position being movable relative to the part of the latch holding the end gate in latched position to enable the release of the door without releasing the end gate, means constantly urging said latches into engagement with the catches, two fingers, one finger on each of said latches, rods slidably mounted on the end gate and extending away from each other, means to operate said rods to cause them to move toward the latches to cause the rods to be engaged with the fingers to enable the operation of the latches to cause the latches to release the catches to enable the operation of the door and the end gate, or either the door or the end gate.

6. In a latch mechanism, a bracket, a shaft mounted in the bracket, two cylinders pivotally mounted on the shaft and having their ends in juxtaposition, a tongue and recess connection between the juxtaposed ends to enable the movement of one cylinder to cause the movement of the other, said recess being much wider than the tongue to enable the movement of one cylinder to take place in advance of the other, a hook on each cylinder adapted to engage with a catch, and a finger on one of the cylinders adapted to be engaged by an operating mechanism to move the cylinders to cause the hooks to be disengaged from their catches.

7. In a latch mechanism, a bracket, a shaft mounted in the bracket, two cylinders pivotally mounted on the shaft and having their ends in juxtaposition, a tongue and recess connection between the juxtaposed ends to enable the movement of one cylinder to cause the movement of the other, said recess being much wider than the tongue to enable the movement of one cylinder to take place in advance of the other, a hook on each cylinder adapted to engage with a catch, cooperating means on the cylinders and on the bracket to limit the movement of the cylinders, and a finger on one of the cylinders adapted to be engaged by an operating mechanism to move the cylinders to cause the hooks to be disengaged from their catches.

PHILIP D. BALDAUF.
